UNITED STATES PATENT OFFICE.

JAMES H. GROVE, OF OMAHA, NEBRASKA, ASSIGNOR, BY MESNE ASSIGNMENTS,
TO AMERICAN ARCH COMPANY, OF NEW YORK, N. Y., A CORPORATION OF NEW
YORK.

LOCOMOTIVE-BOILER FURNACE.

1,033,007.

Specification of Letters Patent. Patented July 16, 1912.

Application filed October 19, 1908. Serial No. 458,525.

To all whom it may concern:

Be it known that I, JAMES H. GROVE, a citizen of the United States, and a resident of Omaha, Douglas county, Nebraska, have 5 invented certain new and useful Improvements in Locomotive-Boiler Furnaces, of which the following is a full, clear, and exact description, such as will enable others skilled in the art to which it appertains to 10 make and use the same.

My invention relates to improvements in locomotive boiler furnaces and has special reference to improvements in lignite burning furnaces.

15 This present invention is a modification of that which is shown and described in my pending application No. 387,442, entitled "Lignite burning furnaces," filed August 7, 1907.

20 This invention is also a modification of that which is shown and described in my pending application No. 458,526, entitled "Locomotive boiler furnaces," filed October 19, 1908.

25 The draft in a locomotive boiler furnace is induced by a blower or exhaust nozzle in the "front end" or smokebox of the boiler, and is such that unless special care is used in firing the furnace, the burning fuel is 30 lifted off of the grate, this is especially the case when lignite is used.

The object of my invention is to provide a locomotive boiler furnace in which lignite may be safely and effectively burned, and 35 my invention consists generally in a locomotive boiler furnace comprising a firebox having a flue sheet at one end and a fuel door at the opposite end in combination with an inclined front hollow arch arranged to deliver air at substantially the center of the 40 box and to project the same downwardly toward the rear end of the box, a second arch occupying a vertical position in the rear part of the box above the front arch and containing 45 air passages and openings for heating and discharging air downwardly into the box adjacent to the end of the front arch, all as and for the purposes hereinafter more fully described and pointed out in the appended claims.

My invention will be more readily understood by reference to the accompanying drawings forming a part of this specification in which:

55 Figure 1 is a vertical section of a locomotive

boiler furnace embodying my invention. Fig. 2 is a plan view thereof, the crown sheet of the firebox being broken away to disclose the arches, Fig. 3 is a vertical section on the line X—X of Fig. 1. Fig. 4 illustrates the invention as applied to fireboxes of the "narrow" type.

In the drawings 2 represents the shell of the boiler; 3 the flues; 4 the flue sheet; 5 the rear sheet of the firebox; 6 the door opening; 7 the fuel door which closes the opening; 8, 8, the side sheets; 9, the crown sheet; and 10 the grate. In the front part of the firebox, extending rearwardly from the flue sheet, 4, is an inclined Wade & Nicholson hollow arch, A. The air is supplied to the ducts, A', through tubes a''. The arch is built up of refractory bricks, and the air passing therethrough is heated to a high temperature. Upon emerging from the ducts, A', the hot air, under high velocity, strikes the refractory deflectors, A''', and is thereby thrown or deflected downward toward the grate and toward the rear end of the firebox.

B is a second arch which extends downwardly from the crown sheet, 9, of the firebox. This arch, as well shown in the drawings, is arranged back of the arch, A, with its lower edge substantially on a level with the top thereof. The arch, B, is preferably supported on studs, B', which project from the side sheets of the furnace. The arch B may be composed of any suitable number of refractory bricks and I prefer to notch or scallop the edges of the bricks which contact the side and crown sheets to permit flow of furnace gases upon said sheets and equalize the temperature thereof. The depending arch, B, preferably occupies a vertical position and is preferably somewhat more remote from the rear sheet of the firebox than from the rear end of the front arch. The dependent or crown arch, B, contains air passages, b, which communicate with the outer air through tubes, b''. The air entering the arch is heated to a high degree and is discharged into the firebox through holes or slots, b''', in the lower edge of the arch. Thus it will be seen that heated air is projected downwardly from both arches and in such quantity as to markedly suppress the rise of pieces and particles of coal. The opening, C, between the two arches is termed the throat of the furnace. The space D be-

low and behind the arches is called the fire chamber and the space, E, above and in front of the arches, A and B is called the combustion chamber. All of the hot gases and combustible products from the fire chamber must pass through the throat, C, to enter the combustion chamber, E. The action of the exhaust nozzle at the front end of the flues creates a partial vacuum in the firebox; hence air rises through the fuel in sufficient quantity to support combustion, and air also enters through the hollow arches, A and B, by which the heated air is thrown downward toward or upon the burning fuel.

It will be noted that the hot air from the arches A and B is projected downwardly substantially across and beneath the throat, C, and its velocity is such as to turn or deflect the gases rising from the fuel, downward and toward the rear end of the firebox, there the currents of gas and air rise behind the depending arch B, and to escape through the throat, C, must pass downward beneath said arch, B. The first effect noted is that the light fuel particles and gases from the fuel instead of being permitted to rise directly to the throat of the furnace are precipitated toward the fuel, the force of the streams of air from the arches, A, and B combining with the reduction of the vacuum above the fuel, due to the admission of air through the arches, and tending to suppress the rise of the gases, fuel particles and cinders. The second effect which is readily observable is the better combustion of the fuel gases and particles due to thorough admixture therewith of fresh air from the front and crown arches. The third and important effect of my arch or furnace construction is that the fuel particles and cinders which are carried up by the currents of air and gas are thrown against the rear side of the vertical arch, B, and losing their velocity fall toward or upon the grate. Their escape into the combustion chamber and into the flues of the boiler is thus prevented.

The good effects of the arches are not restricted to the suppression of the cinders and ashes, but include the complete breaking up of the currents or strata of burned and burning gases, lengthening the travel of the gases in the fire chamber and giving time for their thorough admixture with air and consequent consumption of the light combustibles and particles of carbon given up by the mass of lignite on the grate.

A further and distinct advantage of my invention follows upon the restriction of the throat, C, of the furnace to a comparatively small size through the employment of the vertical hollow arch without covering up the crown sheet of the boiler. It will be noted that only the upper edge of the crown arch is presented to the crown sheet and

that no other part of the crown sheet is covered or protected from the currents of gas. The heat from the fire rises back of the arch as well as in front of it and consequently I retain the even heating of the 70 crown and side sheets of the furnace as in other furnaces, and at the same time secure the numerous advantages before set forth.

As modifications of my invention will readily suggest themselves to one skilled in 75 the art I do not limit my invention to this specific structure herein shown and described.

Having thus described my invention, I claim as new and desire to secure by Let- 80 ters Patent:

1. A locomotive boiler furnace comprising a firebox having a grate and provided with a flue sheet at one end and a fuel door at the opposite end in combination with a 85 crown arch depending from the top of the firebox and supported from the sides of the firebox, said crown arch being adapted to introduce air through itself and project the same downwardly from the lower edge 90 thereof, an inclined front arch between the flue sheet and the crown arch, said front arch containing air passages formed to deflect air downwardly adjacent to the lower edge of said crown arch, substantially as 95 described.

2. A locomotive boiler furnace comprising a fire box having a flue sheet at one end and a fuel door at the other end, in combination with a vertical refractory arch depending from the crown sheet of the furnace, said vertical arch being scalloped and reduced in thickness at the top to cover up but a small area of the crown sheet, air tubes in the side sheets of the furnace, said vertical arch being provided with air conduits communicating with said air tubes and adapted to receive air therefrom and deliver it downwardly through openings in the bottom of the arch, an inclined refractory front arch extending rearwardly from said flue sheet to a point adjacent to the lower edge of said vertical arch, said front arch containing air passages formed to deflect air downwardly and rearwardly adjacent to the lower edge of the said vertical arch, substantially as described. 110

3. A locomotive boiler furnace comprising a firebox having a grate in the lower part and provided with a flue sheet in its front end and a fuel door at its rear end, in combination with an inclined refractory front arch extending rearwardly and upwardly from a point adjacent to the lower portion of said flue sheet to the central portion of the firebox, said arch containing a plurality of air admitting flues having discharge openings arranged and adapted to deliver air downwardly and rearwardly 125 from the upper end of said arch, and a 130

vertically positioned transverse crown arch extending from the top of the firebox downwardly to the central part of the firebox slightly to the rear of the upper end of the front arch, and said crown arch containing air admitting flues having discharge openings arranged and adapted to deliver air downwardly into the firebox.

In testimony whereof, I have hereunto set my hand, this 10th day of October, 1908, ¹⁰ in the presence of two subscribing witnesses,

JAMES H. GROVE.
